ROLLER TRACK

Clarence G. Johnson, Hartford City, Ind.

Application March 18, 1933, Serial No. 661,529

3 Claims. (Cl. 16—96)

This invention relates to an improvement in channel track used in connection with vertical lift doors of the horizontally deflectable type.

An installed door of this type is provided with a track assembly at both vertical margins of the door which assembly is composed of vertical curved and horizontal portions rigidly connected to form a continuous track. The door is held in its vertical position against the frame of the doorway by the engagement with a channel of the track of rollers secured to the margins of the door and is guided during its opening and closing movements by the same channel. When the door is open it is suspended in horizontal position by the support of the horizontal portion of the track for the rollers secured to the door.

In the operation, there is a lateral shifting of the door and consequently of the rollers, which requires some provision to be made to maintain the rollers in the channel of the track. Owing to the length and the approximately right angle formation of the track assembly, it is necessary that the means provided to guide the rollers during lateral shifting of the door does not obstruct the insertion of the rollers in the channel of the track at any point thereof.

An object of the invention is to provide a novel form of track by which the rollers are guided in the main channel thereof against lateral shifting movements of the door and at the same time permits the rollers to be inserted at any point in the vertical portion of the track during installation of the door.

The horizontal portion of the track when the door is open must support the full weight of the door disposed horizontally between the two horizontal tracks. For this purpose another object of the invention is to maintain the rollers from being pulled off the horizontal portion of the track by the weight of the door and to strengthen the horizontal portion of the track against sagging under the weight of the door. The following is a description of an illustrative embodiment of the invention taken in connection with the appended claims and accompanying drawings:

Figure 1 is a substantially medial vertical section through a door installation;

Fig. 2 is a horizontal section on the line 2—2 of Figure 1, showing in cross section the frame of a doorway, the door, the track at each vertical margin of the door and showing in plan a roller in the track and a roller supporting bracket;

Fig. 3 is a rear elevation showing a view of the door on the horizontal portion of the track and

supported by a track at two opposite margins of the door;

Fig. 4 is a detail view partly in cross section of the track, its supporting bracket, and of a roller in the track;

Fig. 5 is a detail view in side elevation of Figure 4;

Fig. 6 is a detail view partly in cross section of a modification of the track;

Fig. 7 is a detail view in side elevation of the track shown in Figure 6;

Fig. 8 is a detail view partly in cross section of another modification of the track;

Fig. 9 is a detail view in side elevation of the track shown in Figure 8;

Fig. 10 is a detail view partly in cross section of another modification of the track;

Fig. 11 is a detail view partly in cross section of the track and the roller showing another arrangement of roller groove and flanges and of a ridge on the tread.

Referring first to the conventional parts of the door illustrated in Figure 1, an outline of a structure of a building consists of a door jamb 1, a header 2, a ceiling joist 3 and a portion 4 of a vertical wall between the header and the ceiling joist.

A door 5 composed of a plurality of panels 6 is hinged at their joints by a hinge 7 and is suspended in vertical position to close the doorway in operative connection with counterbalancing means 8.

At the vertical margins of the door the hinges 7 constitute a bracket carrying a roller stem 9 which extends beyond the vertical margin of the door and at its terminal carries a roller 10. The rollers are positioned to locate the rolling path of the rollers at the vertical side edges of the door and spaced therefrom, and the door seating face is located between the roller axis and the jamb seating face during the vertical travel of the door.

A track 11 is mounted adjacent the jamb of the doorway and is provided with a main channel 12 in which the rollers are disposed to hold the door in vertical position and in which the rollers travel and guide the door during its movements between the vertical and horizontal positions of the door.

A track assembly in an installed door is composed of a vertical portion 11, a curved portion 13, and a horizontal portion 14, rigidly connected to each other to form a continuous track and support for the door in either the vertical or horizontal position. A similar track assembly is positioned at the opposite jamb of the doorway as indicated in Figures 2 and 3.

When the door is opened the rollers guide the door on to the horizontal portions 14 of the track where it is held suspended in horizontal position between the two track assemblies.

5 The present invention more particularly relates to a novel form of track construction as shown in detail in Figures 4 and 5.

The main channel 12 of the track is composed of a flat tread portion 15, a ridged or corrugated

10 tread portion indicated generally at 16 and a web 17 uniting the two tread portions and provided with an inclined wall 18 adjacent the ridged tread portion 16, so as to space the remaining portion of the web away from the rolling path of the rollers.

15 The rollers 10 are provided with annular flanges 19 and the periphery of the roller between the flanges is grooved or channeled as indicated at 20.

20 Due to the manner in which the door is supported by being freely hung adjacent the doorway and supported in place by the rollers in the channel 12 of the track, the said channel forms a barrier for the door edge to guide the door

25 in its movements between the two positions, vertical and horizontal. It will be seen that the movements of the door will be accompanied by some lateral shifting of the door and consequently of the rollers in the main channel 12 of each of the track assemblies at either side of the doorway. The ridge 21, of the tread 16, cooperates with the groove 20 of the rollers to guide the rollers and the door against this lateral shifting.

30 The door margin of the tread 15 is free and provides thereby an opening through which the rollers may be inserted in the channel 12 of the track at any point thereof. The tread 16 is also provided with an upset flange 22 at the door margin of the tread 16. This may be dispensed with as shown in Figs. 8 and 10 but it provides a guard against the roller leaving the main channel of the track. The web of the track may be entirely inclined with respect to the tread 16 as shown in Figures 6 and 8 instead of being partly inclined as shown in Figure 4, or the web may be entirely parallel with the path of the rollers as shown in Figures 10 and 11, without departing from the invention.

35 When the door is opened and therefore disposed horizontally on the horizontal portions of the track assembly or track installation, the weight of the door between the two horizontal portions of the installation tends to pull the rollers laterally of the track or to move the track laterally of the rollers and the full weight of the door being borne by the horizontal portions, there

is a tendency for these portions to sag. With this invention, however, the ridge 16 cooperates with the groove 20 of the rollers to prevent any relative lateral movement between the track and the rollers, and the vertical portions 23 of the ridge 21 prevent sagging of this portion of the track. The upset flange 22 will also cooperate with the track in preventing sagging of the horizontal portion when the door is open.

80 The roller may be provided with a peripheral groove 24 and peripheral flanges 25 which are adapted as shown in Fig. 11 to permit the flanges of the roller to contact with the bottom of the tread 16 instead of the roller groove contacting with the ridge of the tread. This arrangement provides a better bearing surface for the roller and also guides the rollers against lateral shifting movement of the door and it also retains the rollers on the horizontal portions of the track assembly or installation when the door is open.

85 What I claim is:—

90 1. A channel track for a vertical lift and horizontally deflectable door on which a plurality of peripherally grooved single roller units are mounted on horizontally disposed shafts at the vertical 100 margins thereof, said channel comprising a pair of oppositely spaced treads one of which is flat and the other of which has a ridge extending longitudinally thereof and adapted to engage with the groove on the periphery of the rollers to guide the 105 rollers during lateral shifting of the door in its vertical movements.

95 2. In channel tracks for vertical-lift and horizontally-deflectable doors, wherein the door includes a plurality of peripherally-grooved single 110 roller units mounted on horizontally-disposed shafts at the vertical margins of the door, a track having a pair of oppositely spaced treads with either of which a roller unit may contact in service, said treads, in cross-section of the track, presenting one tread as a flat face and the other tread as a rib face substantially complementary to the roller groove configuration, said treads serving to hold the door in vertical position and to guide the door between open and closed positions.

100 115 3. A track as in claim 2 characterized in that the spacing of the treads is that of a distance insufficient to permit removal of a roller unit from the track by movement of the unit in the direction of the roller axis, the complementary configurations of the rib face and roller groove permitting removal of the unit by a pivotal swinging movement of the unit with the rib-face active as the pivot for such swinging movement.
